DRILL PIPE ORIENTING TOOL

Carl St. J. Bremner, Santa Barbara, and Charles M. Potter, Glendale, Calif.

Application April 5, 1935, Serial No. 14,842
Renewed October 19, 1938

17 Claims. (Cl. 255—1)

Our invention relates to a simple means for orienting a drill pipe or other pipe in the bore of a well.

In the drilling of oil wells it has become the practice at certain stages of the drilling operation to orient the drill pipe and whatever device is connected to the lower end thereof for the purpose of determining the position of the drill pipe and of the device, tool, etc., relative to known objects or directions. For example, in the taking of a core it is desirable to know in which direction some indication or marking on the core barrel is facing at the time the core is broken loose from the formation so that when the core is taken from the core barrel, the direction and inclination of the strata may be determined. There are a number of other conditions under which it is desirable to orient a part in a well, among which is the use of a string of drill pipe with fishing tools, deflection tools, and survey machines. The customary practice in orienting drill pipe is by the use of sighting clamps on the drill pipe, which clamps are sighted on some distant object and are moved from joint to joint of the drill pipe as such drill pipe is moved vertically, the intended purpose of such clamps being to keep track of the amount of rotation that takes place while the said pipe is being lowered into the hole or withdrawn from the hole so that the orientation of some lower part or point in the drill pipe may be determined. Such practice cannot compensate for the twists or torque which may occur in the drill pipe as it moves in the hole below the surface of the ground and is therefore out of control of the workers, and the multiplicity of operations in setting and reading the clamps induces personal errors on which there is no check.

Our present invention provides a means and a method for orienting the lower portion of a drill pipe in a well without the use of sight clamps on the drill pipe above the surface of the ground and without the necessity for any attempt to prevent rotation of the drill pipe during its vertical movement.

It is an object of our invention to provide in a string of pipe adapted to be lowered into a well a member, such for, example as a tubular part defining a location or position in the drill pipe, and an orienting member adapted to be moved downwardly through the drill pipe into the previously named member, there being means at such location in the drill pipe for rotating the orienting member on its vertical axis into a definite position relative to a known indication or

marking on the drill pipe, together with an indicator connected to the orienting member or forming a part thereof for showing the position of the orienting member when it is in the known location in the well, the term "position" meaning ordinarily the inclination or the direction in which some known part or indicating member of the orienting member is facing, or both.

In the preferred practice of the invention the location defining member preferably consists of a tube disposed within a drill collar at the lower end of the drill pipe. To this collar any desired attachment or tool may be secured. At any time during the drilling operation the orienting member, with its included recording device, may be lowered into the tubular member, and a record may be procured which will either directly show the position of the drill collar and its attached tool or device, or will give data from which the desired information may be determined.

It is an object of the invention to provide a tubular member which may be incorporated in a string of drill pipe, and preferably in the lower part thereof, having an inwardly faced projection which will be engaged by the orienting member when it is moved downwardly to the tubular member through the string of drill pipe, the orienting member being provided with a spiralled cam which, through its engagement with the projection, will cause the orienting member to rotate into a definite position relative to the projection.

It is a further object of the invention to provide a device of the above character in which the projection set forth in the preceding paragraph is made in the form of a vertically elongated key, and in which the orienting member comprises a bar having a point at its lower end and a pair of oppositely spiralled cam faces leading upwardly from the point of the bar to a slot or pocket in which the key may be received when the orienting member is moved downwardly to the proper position.

It is a further object of the invention to provide a drill pipe with a tubular member having a key therein and a tubular section above the part containing the key which is made of a non-magnetic metal, such, for example, as duralumin, and further to provide at the upper end of the orienting member a simple form of connector, made also of non-magnetic material, for holding the recording device in operative position.

A further object of the invention is to provide a device of the above character in which the position or orientation of the recording device relative to the engaging part of the orienting mem-

ber may be determined or established. This may be considered a means for aligning the respective parts with respect to orientation or means for determining the alignment or disalignment of such parts so that definite corrections may be made in the data obtained from the recording device. For example, the orienting member may be equipped with parts connected together in such a manner that a definite position of the recorder is established relative to the drill pipe and to the tool attached thereto. On the other hand, the cooperating parts of the orienting member may be provided with indicia by which the relative positions of these respective parts, one to the other, may be noted, and from which the exact position of the recording device relative to the keyway or pocket at the lower end of the orienting member may be determined. Since the pocket of the orienting member is automatically rotated into alignment with the key held in the drill pipe, the direction in which the drill pipe and its attached tool or device face may be readily determined from the record produced by the recording device.

It is a further object of the invention to provide a recording device for use as a part of the present invention having a means for showing the relative position or orientation of the record which may consist of a photographic plate, photographic film, or other plates on which the record of orientation, or inclination, or both, is produced.

Further objects and advantages of the invention will be made evident throughout the following part of the specification.

Referring to the drawing, which is for illustrative purposes only:

Fig. 1 is a sectional view showing a preferred form of our invention in operative position in the bore of a well.

Fig. 2 is an enlarged face view of the lower part of the orienting member shown in Fig. 1.

Fig. 3 is a cross section taken as indicated by the line 3—3 of Fig. 1.

Fig. 4 is a view of the lower end of the orienting member.

Fig. 5 is a cross section on a plane represented by the line 5—5 of Fig. 2.

Fig. 6 is a partly sectioned view of the shell employed at the upper end of the orienting member for holding the recording device.

Fig. 7 is an enlarged vertically sectioned view of the recorder which is inserted in the shell shown in Fig. 6 when the orienting device is ready for use.

Fig. 8 is a cross section taken as indicated by the line 8—8 of Fig. 7, to show one form of indicating means.

In Fig. 1 of the drawing we show a drill collar 10 connected to the lower end of a string 11 of drill pipe. This drill collar 10 may have any type of drilling tool or device connected to the lower end thereof, as indicated by dotted lines 12. The drill collar 10 may be properly considered a part of the string of pipe forming the drilling string, and accordingly the key 13 which projects inwardly within the drill collar 10 may be defined as an inwardly faced projection in the drill pipe. The projection or key 13 is preferably secured in place by use of a steel tube 14 which is placed within the drill collar 10 and is held against movement therein by welds 15 at the ends thereof. The tubular member 14 has a vertically elongated opening or slot 16 in the wall thereof through which the key 13 is projected into the

bore 17 forming a part of the axial passage of the string of drill pipe. The key 13 is secured in place by welding it to the wall of the tubular member 14.

Within that part of the string of pipe 11 shown in Fig. 1, we show a member 18, which by reason of its utility may be termed the orienting member. This member has the function of determining the direction in which selected parts of the drilling string face relative to some known direction. Cooperating between the drilling string and the orienting member are parts which automatically cause "radial alignment" of the orienting member with the drilling string, in addition to axial alignment of these parts.

By "radial alignment" is meant the rotation of the orienting member so that a known radial line or plane of the orienting member will coincide with a known radial line of the selected part of the drilling string. In other words, the key 13 definitely defines a radial plane in which the axis of the tubular member 14 lies. When the orienting member is lowered into the position in which it is shown in Fig. 1, it is automatically turned so that a defined or known radial plane extending outwardly from its axis will coincide with the radial plane defined by the key 13. To accomplish this radial alignment, the orienting member 18 has a lower part 21 consisting of a bar formed with an eccentric point 22 (Fig. 2) at its lower end and formed above the point so as to provide a pair of oppositely sloped spiral faces 23. The cam faces 23 at the lower end of the bar 21 face in opposite directions and are substantially parallel. As these cam faces swing upwardly, they rotate through angles of nearly 180°, so that the upper end portions 24 thereof are parallel, but face each other, and form the mouth of a pocket or slot 25 which extends vertically in the face of the bar 21 and is of such width that it will receive the key 13. The upper end of the slot 25 stops at a shoulder 26 which rests against the upper end of the key 13 when the orienting member is lowered into a position of complete engagement with the key 13.

The upper end of the key 13 is preferably sharpened to wedge or chisel shape, and when the downwardly moving orienting member 18 reaches the key 13, one of the cam faces 23 will engage the upper portion of the key 13, and as the orienting member 18 continues to move downwardly, the reaction of the cam face 23 against the key 13 will cause the orienting member 18 to rotate so that the key 13 will finally align with the slot or pocket 25 and will relatively move upwardly in the slot 25 to the stop or shoulder 26 at the upper end thereof.

A recording device is connected to or forms part of the orienting member 18. Devices of this character are well known, and a number of such devices are now being made operating on different principles. For example, in such device may be a compass either of magnetic or gyroscopic character, and a dial against which the position of the compass needle may be viewed, together with means for indicating the inclination of the supporting structure carrying the recording device. The record of the compass reading and inclination, at a desired time, may be obtained mechanically or photographically. In view of the fact that devices of this character are well known, we shall not attempt to illustrate the same herein in detail. For simplicity of illustration we merely show in diagrammatic form a recording device 30 disposed within a

sleeve 31 which forms the upper part of the orienting member 18.

The sleeve 31 may be open at its lower end and may be connected to the bar 21 by means of a section 32 of non-magnetic metal. The sleeve 31 is also made from non-magnetic metal, as is also the length or section 33 of pipe which forms a part of the drilling string 11 immediately above the collar 10 so that the recording device 30 will 10 be entirely surrounded by non-magnetic metal. As shown in Fig. 6, the sleeve member 31 is internally threaded at its lower end and has a key 34 near the upper end thereof, which key 34 may 15 be engaged by an aligning slot 35 in the upper part of the shell 36 of the recording device 30. When the recording device 30 is placed in the opening 37 within the sleeve 31, the slot 35 is caused to receive the key 34 so that the recording device 30 will be moved into a definite position 20 of alignment with the key 34. As shown in Fig. 1, the exterior of the sleeve 31 has a mark 38 thereon which may be caused to assume a position, such as a position of alignment, relative to a mark 39 on the upper end of the connecting member 32, when the parts 31 and 32 are screwed together. Likewise the lower end of the connecting member 32 may have a mark 40 which may 25 be caused to assume a definite relation to a mark 41 on the upper end of the lower part or 30 bar 21 of the orienting member 18. Accordingly, the orienting member 18 has means for orienting the recording device 30 with the slot or pocket 25 at the lower end of the orienting device, and the record which is produced in the recording 35 device is therefore a means for orienting, or determining the position of, the key 13 which forms the projection within the drill pipe and which indicates the axial alignment of the part, tool, or device 12 which may be secured to the lower 40 end of the drill pipe. For the purpose of aligning the member 12 with the key 13, or orienting the same relative to the key 13, a narrow channel or mark 44 may be formed in the lower end of the drill collar 10 in the same radial plane as the key 13. Furthermore, the key 13 may be referred to as a reference member for the reason 45 that it faces in a known direction with reference to the mark 44 on the member 10 or some known portion of the tool 12 which is connected to the member 10. Likewise, the key 13 is the part 50 with reference to which the orienting member is positioned before the record is made.

The upper end of the sleeve member 31 is connected to a non-magnetic bar 45 which may be 55 provided with threads 46 to which a cable socket 47 may be secured so that a cable or wire line 48 may be secured for the purpose of lowering the orienting member 18 down through the drill pipe 11 and then lifting the orienting member 18 60 again to the surface after the records of orientation and inclination have been obtained by the recording device 30. This we believe to be a preferred manner of using the invention in view of the fact that it enables the operator to obtain 65 a record of orientation or inclination, or both, through the simple expedient of lowering the orienting member down through the string of drill pipe on a wire line and again pulling it to the surface. This new method of use avoids 70 the necessity of pulling the drill pipe to bring a recording device to the surface, but it is to be understood that the inclusion of this preferred method does not place any limitation upon the use of the device, since it may be moved down- 75 wardly into the well to recording position, and

then removed from the well, in other manners. For example, the orienting member may be pumped down through the string of drill pipe and left in place in the tool joint 10 until the string of drill pipe is raised to the surface. Likewise, the orienting member may be pumped down through the drill pipe to its position of operation and may be then removed by flotation or by reversing a flow of drilling liquid upwardly through the interior of the drill pipe to pump the orienting member to the surface.

The orienting device further provides a means for orienting the record relative to the remaining part of the equipment. As previously explained, the slot 35 in the shell 36 of the recording device 30, engaging the key 34 within the shell 31, aligns the case or shell 39 of the orienting device with the key 34 and likewise with the markings 38, 39, 40, and 41. As diagrammatically shown in Fig. 7, the record may consist of 20 a photographic plate 50 which may be made of paper with a sensitized coating, and which is insertable and removable through a slot 51 in the side of the casing or shell 30 and which may be pressed into operative position against a glass plate 52 by means of a rotatable block 53 having a spiral cam thereon for causing its vertical movement when it is rotated. Disposed within the shell 30 at a distance above the record or plate 50, is a compass 54 which floats in a chamber of liquid 55, having a transparent lower wall 56. Small lights 57 are disposed in such position that light will be reflected from the compass 54 downwardly through a lens 58 to the sensitized record plate 50. A pendulum 60 is disposed just above the plate 50 so as to intercept light rays which are passing to the plate 50 and thereby record its position. Projecting inwardly from the wall of the shell 36, in a position relatively close to the glass 52, is a pointer 61 which is preferably aligned with the slot or keyway 35. This pointer 61 also intercepts light rays which are passing downwardly toward the sensitized plate 50 so as to leave a record of the position of the pointer 61 on the sensitized plate, thereby producing an indication on the sensitized plate, and likewise on the record which is developed from the sensitized plate, whereby the record may be oriented relative to the keyway 35 and the remaining parts of the orienting device. The type 50 of recording device which we have shown in Fig. 7 has flashlight batteries 63 contained in a compartment at the lower end thereof, and also has a time controlled switch 64 for connecting the batteries 63 and the lamps 57 in circuit at a given time, whereby to produce the light rays necessary for transmitting the images of the compass, pendulum, and pointer to the sensitized plate 50.

Although we have herein shown and described our invention in simple and practical form, it is recognized that certain parts or elements thereof are representative of other parts, elements, or mechanisms which may be used in substantially the same manner to accomplish substantially the same results; therefore, it is to be understood that the invention is not to be limited to the details disclosed herein but is to be accorded the full scope of the following claims.

We claim as our invention:

1. An orienting device of the character described for use with a string of pipe adapted to be lowered into a well, including: a tubular member forming a part of said string of pipe, said tubular member having an inwardly faced pro-

jection; and an orienting member adapted to be moved downwardly through said string of pipe to said tubular member, said orienting member comprising a lower part having a spiral cam face leading upwardly to a pocket, said cam face being adapted to engage said projection and cause rotation of said orienting member to bring said pocket into alignment and engagement with said projection, a non-magnetic member connected 10 to the upper end of said lower part, said non-magnetic member comprising a sleeve with an inwardly projecting key, and a container for a recording device adapted to be inserted in said sleeve so as to be held therein, said container 15 having a keyway for engaging said key so as to hold said container in a definite position of orientation relative to said sleeve, and said recording device having a record element upon which it reproduces an indicia showing the radial 20 position of said record relative to said tubular member.

2. An orienting device of the character described for use with a string of pipe adapted to be lowered into a well, including: a tubular member forming a part of said string of pipe, said tubular member having an inwardly faced projection; and an orienting member adapted to be moved downwardly through said string of pipe to said tubular member, said orienting member 25 comprising a lower part having a point at the lower end thereof and a pair of oppositely spiralled cam faces leading upwardly to a pocket for receiving said projection, either of said cam faces being adapted to engage said projection 30 and cause rotation of said orienting member to bring said pocket into alignment and engagement with said projection, a non-magnetic member connected to the upper end of said lower part, said non-magnetic member comprising a sleeve 35 with an inwardly projecting key, and a container for a recording device adapted to be inserted in said sleeve so as to be held therein, said container having a keyway for engaging said key so as to hold said container in a definite position 40 of orientation relative to said sleeve, and said recording device having a record element upon which it reproduces an indicia showing the radial 45 position of said record relative to said tubular member.

50 3. In combination, a hollow drill stem; a tool carried by the drill stem as the instrument is lowered and adapted to be oriented by rotation of the stem; an instrument arranged to pass through the drill stem and arranged to occupy 55 a predetermined final longitudinal position therein adjacent the tool, said instrument containing means for indicating orientation, and means for recording the indication of the orientation indicating means; and interengaging means 60 on the inside of the drill stem and the outside of said instrument for effecting rotary movements of the instruments relative to the drill stem for causing the instrument to assume a predetermined position relative to said tool when in said 65 final longitudinal position.

4. In combination, a hollow drill stem; a tool carried by the drill stem and adapted to be oriented by rotation of the stem; an instrument arranged to pass through the drill stem and arranged 70 to occupy a predetermined final longitudinal position therein adjacent the tool, said instrument containing means for indicating orientation, and means for recording the indications of the orientation indicating means; said 75 drill stem including a hollow element of reduced

bore at said predetermined position to receive at least part of said instrument and substantially align it with the axis of the drill stem, and interengaging means on the inside of the drill stem and the outside of said instrument for effecting 5 rotary movements of the instrument relative to the drill stem as the instrument is lowered for causing the instrument to assume a predetermined position relative to said tool in said final longitudinal position. 10

5. In combination, a hollow drill stem; a tool carried by the drill stem and adapted to be oriented by rotation of the stem; an instrument arranged to pass through the drill stem and arranged to occupy a predetermined final longitudinal position therein adjacent the tool, said instrument containing means for indicating inclination and means for recording the indications of the inclination indicating means; and interengaging means on the inside of the drill stem 15 and the outside of said instrument for effecting rotary movements of the instrument relative to the drill stem as the instrument is lowered for causing the instrument to assume a predetermined position relative to said tool when in said 20 final longitudinal position.

6. In combination, a hollow drill stem; a tool carried by the drill stem and adapted to be oriented by rotation of the stem; an instrument arranged to pass through the drill stem and arranged to occupy a predetermined final longitudinal position therein adjacent the tool, said instrument containing means for indicating inclination and means for recording the indications of the inclination indicating means; said 30 drill stem including a hollow element of reduced bore at said predetermined position to receive at least part of said instrument and substantially align it with the axis of the drill stem, and interengaging means on the inside of said bore and 35 the outside of said instrument for effecting rotary movements of the instrument relative to the drill stem as the instrument is lowered for causing the instrument to assume a predetermined position relative to said tool in said final longitudinal 40 position. 45

7. In combination, a hollow drill stem; a tool carried by the drill stem and adapted to be oriented by rotation of the stem; an instrument arranged to pass through the drill stem and arranged to occupy a predetermined final longitudinal position therein adjacent the tool, said instrument containing means for indicating inclination and means for recording the indications of the inclination indicating means; said 50 drill stem including a hollow element of reduced bore at said predetermined position to receive at least part of said instrument and substantially align it with the axis of the drill stem, and means for designating the oriented relationship of the 55 instrument and drill stem when the instrument is in said final longitudinal position. 60

8. The method of orienting a tool within a bore hole including lowering the tool into the bore hole on a hollow drill stem, the lower portion of 65 which drill stem carries an engaging element, lowering within the drill stem an instrument containing means for indicating azimuth and means for recording the indications of the azimuth indicating means, said instrument being provided 70 with an engaging element arranged, in cooperation with the first mentioned engaging element, to turn and orient said instrument relative to the drill stem, said lowering of the instrument being 75 to a point where said elements cooperate to turn 80

and orient said instrument relative to the drill stem; thereafter causing said recording means to operate; withdrawing said instrument; and rotating the drill stem to bring the tool into a predetermined azimuthal position.

9. The method of orienting a tool within a bore hole including lowering the tool into the bore hole on a hollow drill stem, the lower portion of which drill stem carries an engaging element, lowering within the drill stem an instrument containing means for indicating inclination and means for recording the indications of the inclination indicating means, said instrument being provided with an engaging element arranged, in cooperation with the first mentioned engaging element, to turn and orient said instrument relative to the drill stem, said lowering of the instrument being to a point where said elements cooperate to turn and orient said instrument relative to the drill stem; thereafter causing said recording means to operate; withdrawing said instrument; and rotating the drill stem to bring the tool into a predetermined azimuthal position.

10. A well surveying apparatus comprising a sleeve fixed within a drill string and having an open upper end, a well surveying instrument adapted to be lowered within the drill string, said instrument being fitted at its lower end with a mandrel which will seat within the sleeve, cooperating means between the mandrel and the sleeve for placing the mandrel in a position of known orientation with relation to the sleeve, means within the instrument to produce a record indicating the direction of the declination of the drill string, and means acting automatically to produce said record when the instrument is seated within the sleeve.

11. A well surveying apparatus comprising a sleeve fixed within a drill string and having an open upper end, a well surveying instrument adapted to be lowered within the drill string, said instrument being fitted at its lower end with a mandrel which will seat within the sleeve, cooperating means between the mandrel and the sleeve for placing the mandrel in a position of known orientation with relation to the sleeve, means within the instrument to produce a record indicating the direction of the declination of the drill string and the degree of the same, and means acting automatically to produce said record when seated within said sleeve.

12. A well surveying device comprising a sleeve adapted to be mounted within a drill string, a well surveying instrument adapted to be lowered within the drill string, said instrument comprising a mandrel at its lower end which is lowered to a fixed seated position both longitudinally and circumferentially within said sleeve, and means for rotating the mandrel to a definite position of orientation with relation to the sleeve, and means for producing a record within the instrument indicating the position of orientation of the instrument, and means for producing said record when the mandrel has reached its fixed position with relation to the sleeve.

13. A well surveying apparatus comprising a drill string carrying a tool in a known fixed position of orientation with respect to the drill string, an instrument catcher within the drill string adjacent its lower end, a recording instrument adapted to be lowered through the drill string to a seated position within the catcher, cooperat-

ing means between the catcher and the instrument to rotate the instrument to a fixed seated position of orientation with relation to the catcher, a recording element within the instrument held in fixed relation to the instrument, means within the instrument responsive to declination of the instrument, and means acting when the instrument has reached its seated position within the catcher to produce a record of declination upon the recording element.

14. Means for positioning a tool in a well comprising a drill line, said line including a tubular section having a longitudinally extending key therein, said section being located above the tool, an elongated aligning pin for fitting in the tubular section, said pin having a longitudinally extending keyway therein having its lower end open for receiving the key, means on the aligning pin for automatically directing the key into the keyway as the aligning pin is lowered into the key carrying section, said key being in predetermined relationship with the tool, a photographic surveying instrument connected to the upper end of the aligning pin and including a compass, a marker positioned in alignment with the keyway, and means for photographically recording the relative positions of the marker and compass, and means for lowering the instrument with the aligning pin thereon into the drill line and for removing said parts from the drill line.

15. A well surveying apparatus comprising a catcher disposed in a fixed position both longitudinally and circumferentially within a drill pipe, said pipe carrying a tool at its lower end fixed in known orientation with the pipe, a well surveying instrument adapted to be lowered into the drill string and to a fixed position of rest within said catcher, cooperating means between the catcher and the instrument for designating the oriented relationship of the catcher and instrument when the instrument comes to rest, and means within the instrument to produce a record indicating the oriented position of the instrument relative to the catcher.

16. A well surveying apparatus comprising a catcher disposed in a fixed position both longitudinally and circumferentially within a drill pipe, said pipe carrying a tool at its lower end fixed in known orientation with the pipe, a well surveying instrument adapted to be lowered into the drill string and to a fixed position of rest within said catcher, cooperating means between the catcher and the instrument for designating the oriented relationship of the catcher and instrument when the instrument comes to rest, and means within the instrument to produce a record indicating the oriented position of the instrument relative to the catcher and the degree of declination of the drill string.

17. A well surveying apparatus comprising a catcher within a drill pipe, a tool carried by the pipe and with which said catcher is in known orientation, a well surveying instrument adapted to be lowered through the drill pipe to a position of rest within the catcher, cooperating means between the instrument and the catcher for designating the oriented relationship of the catcher to the instrument when the instrument comes to rest, and means for making a record of the oriented relationship of the instrument to said tool.

CERTIFICATE OF CORRECTION.

Patent No. 2,207,505.

July 9, 1940.

CARL ST. J. BREMNER, ET AL.

It is hereby certified that error appears in the printed specification of the above numbered patent requiring correction as follows: Page 4, first column, lines 51 and 52, claim 3, strike out the words "as the instrument is lowered" and insert the same after "stem" in line 62, same claim; line 62, same claim 3, for "instruments" read --instrument--; and that the said Letters Patent should be read with this correction therein that the same may conform to the record of the case in the Patent Office.

Signed and sealed this 17th day of September, A. D. 1940.

Henry Van Arsdale,
Acting Commissioner of Patents.
